UNITED STATES PATENT OFFICE.

JOHN QUINCY REED, OF NEW YORK, N. Y., ASSIGNOR TO THE BUTTERICK PUBLISHING CO., (LIMITED,) OF SAME PLACE.

DESIGN FOR A MISS'S KILT-PLAITED SKIRT WITH SASH DRAPERY.

SPECIFICATION forming part of Design No. 14,370, dated October 23, 1883.

Application filed August 23, 1883. Term of patent 3½ years.

To all whom it may concern:

Be it known that I, JOHN QUINCY REED, of the city, county, and State of New York, have invented and produced a new and original Design for a Pattern of a Miss's Kilt-Plaited Skirt with Sash Drapery, (numbered 8,843;) and I do hereby declare that the engraved prints accompanying this specification convey to any one accustomed to using paper patterns a clear understanding of how a garment made up by the pattern will appear.

The design combines a side-plaited skirt-

section and a deep fitted yoke with a sash drapery composed of a scarf and a sash-bow.

What I claim as my invention, and desire to secure by Letters Patent, is—

The design for a miss's kilt-plaited skirt with sash drapery, as shown in the engraved prints accompanying this specification.

JOHN QUINCY REED.
